UNITED STATES PATENT OFFICE.

ARTHUR A. HUEBSCH, OF CONGRESS PARK, ILLINOIS.

DESIGN FOR A SERVICE-FLAG OR SIMILAR ARTICLE.

55,273.

Specification for Design.

Patented May 25, 1920.

Application filed September 19, 1918. Serial No. 254,876. Term of patent 3½ years.

To all whom it may concern:

Be it known that I, ARTHUR A. HUEBSCH, a citizen of the United States, and residing in the village of Congress Park, county of Cook, and State of Illinois, have invented a new, original, and ornamental Design for a Service-Flag or Similar Article, of which the following is the specification, reference being had to the accompanying drawing, forming a part thereof.

In the drawing:

The figure is a front view of a flag showing my new design.

I claim:

The ornamental design for a service flag or similar article, as shown.

ARTHUR A. HUEBSCH.
